UNITED STATES PATENT OFFICE.

EDMOND CHAMPAGNE, JR., OF ALBION, RHODE ISLAND.

LINT-REMOVER FOR ELECTRICAL WARP STOP-MOTIONS.

No. 902,857.

Specification of Letters Patent.

Patented Nov. 3, 1908.

Application filed May 6, 1908. Serial No. 431,236.

To all whom it may concern:

Be it known that I, EDMOND CHAMPAGNE, Jr., citizen of the United States, residing at Albion, in the county of Providence and State of Rhode Island, have invented new and useful Improvements in Lint-Removers for Electrical Warp Stop-Motions, of which the following is a specification.

My invention relates to lint-removers for electrical warp stop motions, of the type embodying a contact-roll, drop-bars or detectors suspended on warp threads and each adapted in the event of its warp thread breaking to co-operate with the contact-roll and close an electric circuit, and thereby put in operation a spring-actuated shipper or other means for stopping the loom, and means for wiping deposits of lint or the like from the contact-roll on rotation of said roll.

One object of my invention is to provide in combination with the contact-roll in circuit closing means such as described, means arranged to derive motion from a working part of a loom and to turn the contact-roll, incidental to operation of the loom, against means for removing lint from said roll, this being advantageous inasmuch as it assures the contact-roll presenting a clean surface to any drop-bar or detector that may fall and precludes the possibility of lint on the roll being fired by an electric spark due to poor contact.

Another object of the invention is to provide means arranged to be operated by a working part of the loom and to rotate the lint-removing means during the working of the loom so as to increase the efficiency of said lint-removing means by presenting a fresh surface thereof at frequent intervals to the contact-roll.

With the foregoing in mind the invention will be fully understood from the following description and claims when the same are read in connection with the drawings, accompanying and forming part of this specification, in which:

Figure 1 is a view, partly in elevation and partly in vertical section of so much of a loom as is necessary to illustrate the application of my improvements, it being understood that generally speaking the loom is constructed in the ordinary well known manner. Fig. 2 is a section taken in the plane indicated by the line 2—2 of Fig. 1; and showing the toothed warp beam and toothed wheel not shown in Fig. 1. Fig. 3 is a perspective view illustrating

the electrically controlled means for putting the shipper in operation *i. e.*, enabling the lay of the loom to knock off the shipper.

Similar letters of reference designate corresponding parts in all of the views of the drawings, referring to which:

A are the frame sides of the loom to which are connected brackets B, carrying lease rods C over and under which warp threads are alternately passed, as usual. Disposed below the lease rods and secured between the frame sides A are parallel circuit bars D, and suspended from the warp threads and resting in engagement with the circuit bars are drop-bars or detectors E, which latter are designed in the event of the warp threads breaking to gravitate and touch the contact roll F which is located below the drop-bars in the manner clearly illustrated in Fig. 2. There is one drop-bar or detector to each warp thread, and the circuit bars D are electrically connected through the loom frame and other means with one pole of a battery or other source of electric energy G, while the contact roll F is electrically connected with the other pole of said battery. In the electrical circuit with the bars D, the contact roll F and the battery G is a suitable electro-mechanical device H, preferably an electro-magnet, which is designed when the normally open circuit is closed by the breaking of a warp thread and the falling of the drop-bar complementary to said thread against the contact roll F, to move an armature lever I and thereby raise a latch J connected with said lever into the path of a dagger on a lay (not shown), so that on the following stroke of the lay the dagger will strike the latch and a knock-off K connected with the latch and through the medium of the said knock-off will strike a shipper L and disengaging the same from a notch in a guide-plate M will permit the shipper to spring inward and operate the belt shifter in the usual manner to stop the loom.

In carrying out my invention I provide the contact-roll F at one end with teeth *a*, and employ in combination with the said toothed roll, a wheel M having a tappet *b* arranged to engage the teeth *a* of the roll and also arranged to turn the roll through a part of a revolution incidental to each revolution of the wheel M.

I prefer to drive the wheel M from the warp beam P of the loom, and when expedient to connect the warp beam with the said

wheel through the medium of intermeshed spur gear teeth *c* and *d* on the beam and wheel, respectively. I would have it understood, however, that when my invention is applied to a loom, the warp beam of which has no spur gear teeth, any suitable driving connection may be provided between the beam and the wheel to rotate the latter by the former.

10 By virtue of the contact - roll *F* being turned as stated during the working of the loom, it will be manifest that a wiper in engagement with the periphery of the contact-roll will be enabled to keep the said periphery clean and free from lint so as to assure a perfect contact between the roll and one of the drop-bars when the latter drops on the former, and in this connection I would have it distinctly understood that any suitable 15 means may be employed for wiping the contact - roll *F*, without involving departure from the scope of my invention as defined in the claims appended. I prefer, however, to employ for wiping the contact-roll, a roll *S* the periphery of which may be equipped with wiping means such for instance as a textile covering *e*. The said roll *S* is preferably provided with teeth *f* and is preferably rotated by the engagement of the before-described 20 tappet *b* with the said teeth *f*. It will thus be seen that during the operation of the loom, first the contact-roll *F* and then the wiping roll *S* will be rotated but in opposite directions, with the result that the roll *S* will positively operate to remove lint from the periphery of the roll *F*. It will be noticed in this 25 connection that different parts of the periphery of the roll *F* are presented to different parts of the roll *S*, which obviously conduces to the entire periphery of the roll *F* being 30 kept entirely clean.

Having described my invention, what I claim and desire to secure by Letters-Patent, is:

45 1. In lint removing means for electrical warp stop motions, the combination with the contact-roll of circuit closing means, a roll for wiping the contact-roll, a working part of the loom, and means intermediate

the said working part and the contact-roll 50 and wiping roll for rotating said rolls by movement of said part.

2. In lint removing means for electrical warp stop motions, the combination with a contact-roll having teeth at one end, and 55 means for wiping the said roll, of a warp beam, a wheel, means on the wheel for engaging the teeth of the contact-roll and turning the latter, and a driving connection intermediate the warp beam and the wheel. 60

3. In lint removing means for electrical warp stop motions, the combination with a contact - roll comprised in circuit closing means and having teeth at one end, and a roll for wiping the contact-roll also having 65 teeth at one end, of a warp beam, a wheel, means on the wheel for engaging the teeth of the contact-roll and the teeth of the wiping roll and turning said rolls in opposite directions, and a driving connection intermediate 70 the warp beam and the wheel.

4. In lint removing means for electrical warp stop motions, the combination with a contact - roll comprised in circuit closing means and having teeth at one end, and a 75 roll for wiping the contact-roll also having teeth at one end, of a warp beam, a wheel, a driving connection intermediate the warp beam and the wheel, and a tappet on the wheel arranged to engage the teeth of the 80 said rolls and turn the rolls in opposite directions.

5. In lint removing means for electrical warp stop motions, the combination with the contact-roll of circuit closing means, of a 85 roll for wiping the contact-roll having teeth at one end, a warp beam, a wheel, a driving connection between the warp beam and the wheel, and means on the wheel for engaging the teeth of the wiping roll and rotating the 90 latter.

In testimony whereof I have hereunto set my hand in presence of two subscribing witnesses.

EDMOND CHAMPAGNE, JR.
